CLAIM

The ornamental design for a display screen with animated graphical user interface, as shown and described.

DESCRIPTION

FIG. 1 is a front view of a first image in a sequence for a display screen with animated graphical user interface showing our new design;

FIG. 2 is a front view of a second image thereof;

FIG. 3 is a front view of a third image thereof;

FIG. 4 is a front view of a fourth image thereof;

FIG. 5 is a front view of a first image in a sequence of a second embodiment of a display screen;

FIG. 6 is a front view of a second image thereof;

FIG. 7 is a front view of a third image thereof; and,

FIG. 8 is a front view of a fourth image thereof.

The appearance of the image sequentially transitions between the images shown in FIGS. 1 through 4, and FIGS. 5 through 8, respectively. The process or period in which one image transitions to another forms no part of the claimed design.

The outermost broken lines illustrate the environment of the design and form no part of the claimed design. The remaining broken lines illustrate the display screen and portions of the graphical user interface that form no part of the claimed design.

1 Claim, 8 Drawing Sheets
